The drawing is a plan view of a paper towel section showing my new design, a full width of the design being shown with the design unit being repeated in regular succession to an indeterminate length, the upper and lower ends of the design, as shown, representing the upper and lower ends of a typical paper towel section previously connected to adjacent paper towel sections by serrations; the background embossed or dimpled configuration of the paper towel is shown at the lower left hand corner, the remainder of the background having been omitted for convenience of illustration.

I claim:

The ornamental design for paper toweling, as shown and described.
